BELL FOR BLAST FURNACES

Edgar P. Everhard, Chicago, Ill., assignor to
Freyn Engineering Company, Chicago, Ill., a
corporation of Maine

Application April 9, 1931. Serial No. 528,735

2 Claims. (Cl. 214—36)

12 The present invention relates to improvements
in bells for blast furnaces.

In modern blast furnace practice it has become
desirable to provide bells of large size. Such bells
5 present difficulties in the process of casting as
well as difficulties in shipment and in repairs.

An object of the present invention is to provide
a blast furnace bell made up of a plurality of
parts, each of which is relatively simple to manu-
10 facture, which parts are also simple to assemble
into an operative structure.

A further object is to provide a multiple piece
blast furnace bell in which the matter of repairs
is simplified.

15 A further object is to provide an efficient blast
furnace bell which may be manufactured at a
minimum cost.

Further objects will appear as the description
proceeds.

20 Referring to the drawing—

Figure 1 is a top plan view of one embodiment
of the present invention;

Figure 2 is a sectional view taken along the
plane indicated by the arrows 2—2 of Figure 1;

25 Figure 3 is an enlarged view of a part of the
structure shown in Figure 2;

Figure 4 is a side view of a wedging member or
pin and cooperating key shown in operative position
30 in the practice of the present invention; and

Figure 5 is a view illustrating said wedge pin
in operative relationship with the remainder of
the bell.

The blast furnace bell chosen for illustration
35 comprises an upper bell-shaped portion 10 and a
bottom portion 11. The upper portion 10 will
preferably be an integral member and will be
provided with the usual structure at its center by
means of which the bell may be hung in the cus-
tomy way. For this purpose the upper portion

40 10 is provided with the downwardly extending
boss 12 provided with the strengthening ribs
13—13. The boss 12 may be provided with the
pair of apertures 14—14 for the reception of a
holding means for a cable (not shown) for con-
trolling the bell.

The bottom portion 11 of the bell may be made
in one piece if desired, but preferably will be
made in a plurality of pieces bolted together. In
50 the illustrated embodiment of the present inven-
tion the bottom portion 11 is made up of four
sections 15—15, which sections are provided at
their extremities with the inwardly extending
flanges 16—16. When the sections 15—15 are
55 in assembled relationship with one another the
flanges 16—16 are disposed in radial relationship

to a common center. Bolts 17—17 are provided
which cooperate with the flanges 16—16 to hold
the sections 15—15 in assembled relationship to
provide an annular tapered member. The lower
extremity of the upper portion 10 is provided with
60 the outwardly presented conical surface 18, which
preferably should be a finished surface. The
upper portion of the bottom portion 11 is pro-
vided with the inwardly presented conical surface
19 adapted to cooperate with the conical surface
65 18. The upper portion 10 of the bell is provided
with a plurality of apertures 20—20 for the recep-
tion of pins 21—21. Said pins 21—21 have
wedge-shaped head portions 22 adapted to have
70 wedging relationship between the upper extremi-
ty of the bottom portion 11 and the shoulder 23 of
the upper portion 10 of the bell. Taper keys
24—24 are provided for holding the wedge pins
21—21 in operative position.

The top portion 10 and each of the sections
75 15—15 of the bottom portion 11 may be readily
cast or otherwise manufactured with the ordinary
equipment found in foundries or other factories.
The sections 15—15 of the lower portion 11 of
the bell may be bolted together and slipped over
80 the upper portion 10 with the cooperating conical
surfaces 18 and 19 in engagement with one an-
other. The wedge pins 21—21 may then be driven
in, wedging the top portion 10 with the bottom
portion 11 into rigid relationship with one an-
other, after which the keys 24—24 may be driven
85 home. The bell may then be completely ma-
chined in assembled condition, after which the
parts may be dismantled and shipped to the job,
where they may be readily secured together
90 within the furnace in which the bell is to be used.
By reason of the present invention the lifting
of heavy weights even in the use of large bells is
avoided.

An advantage of the present invention is that
95 repairs to the bell or assembly thereof are possi-
ble without completely dismantling the top. For
example, if one section 15 of the bell should be
burned or cracked, this section could be removed
by unbolting said section from its neighboring
100 sections and removing the wedge pins 21—21
cooperating with that particular section. The
burned or cracked section could then be dropped
into the furnace and the new section to replace
it could be lowered through the gas seal in a man-
ner well understood to those skilled in blast fur-
nace practice.

Though a preferred embodiment of the pres-
ent invention has been described in detail, many
modifications will occur to those skilled in the
110

art. It is intended to cover all such modifications that fall within the scope of the appended claims.

What is claimed is—

1. A blast furnace bell comprising a central portion having an outwardly presented conical surface and a skirt portion having an inwardly presented conical surface bearing upon said outwardly presented conical surface, and a plurality of spaced pins extending through said upper portion, 5 said pins having tapered heads having wedging relationship between the upper extremity of said lower portion and said upper portion.

10 2. A blast furnace bell comprising a central

portion having an outwardly presented conical surface and a skirt portion having an inwardly presented conical surface bearing upon said outwardly presented conical surface, and a plurality of spaced pins extending through said upper portion, 80 said pins having tapered heads having wedging relationship between the upper extremity of said lower portion and said upper portion, 85 said pins being provided with tapered keys disposed inwardly of said bell for holding said pins in operative relationship with said portions.
